(57) **CLAIM**

The ornamental design of the cigarette lighter adapter, as shown and described.

DESCRIPTION

FIG. 1 is a perspective view of the cigarette lighter adapter.

FIG. 2 is a back view of the cigarette lighter adapter.

FIG. 3 is a front view of the cigarette lighter adapter.

FIG. 4 is a top view of the cigarette lighter adapter, the bottom plan view being a mirror image; and,

FIG. 5 is a side view of the cigarette lighter adapter, the opposite side view being a mirror image.

The broken lines are shown for illustrative purposes only and form no part of the claimed design.
